(57) **CLAIM**

The ornamental design for a vehicle body, as shown and described.

DESCRIPTION

FIG. 1 is a front view of a vehicle body showing the new design;

FIG. 2 is a right front perspective view thereof;

FIG. 3 is a right side view thereof, the left side being a mirror image thereof;

FIG. 4 is a right rear perspective view thereof;

FIG. 5 is a top view thereof; and,

FIG. 6 is a rear view thereof.

In the drawings, the elements shown in broken lines are for illustrative purposes only and form no part of the claimed design.
